STIRRING MACHINE

Filed June 18, 1928

By Chas Williamson
Attorney

UNITED STATES PATENT OFFICE

ROLLER E. DUTT, OF TIFFIN, OHIO

STIRRING MACHINE

Application filed June 18, 1928. Serial No. 236,425.

In the manufacture or production of potato chips the slices of raw potatoes are placed in a large kettle of lard which is heated for cooking. A kettle about four feet in diameter 5 is used. Cooking requires seven or eight minutes and during the cooking operation, it is necessary to stir the slices or chips. The object of my invention is to provide an efficient yet a simple device by which the necessary stirring may be accomplished.

My invention consists in whatever is described by or is included within the terms or scope of the appended claim.

In the drawing:

15 Figure 1 is a perspective view of a stirrer embodying my invention.

Fig. 2 is a detail view of the stirrer rotat- ing gearing.

Describing by way of preliminary, the embodiment of my invention shown in the drawing, it comprises two sets of rotary fingers that rotate in opposite directions to counteract or prevent any displacement of the chips or slices, a frame that supports the shafts 25 of such fingers which may swing vertically to place the fingers in the kettle and to lift them therefrom, motor-driven means to rotate the fingers and a base or support upon which the various members are mounted and 30 by which the same are held in proper relative position with the kettle.

Describing in detail what is shown in the drawing, the base 10, is a horizontal board adapted to rest upon some convenient support near the kettle (not shown in the drawing) which may be a stand or other article of proper height, and bolted to the upper side of said base is a light metal frame-work, 11, which has at the top bearings for a horizontal shaft, 12, to which is fixed a worm-wheel, 13, engaged by a worm, 14, on a horizontal shaft, 15, mounted below the worm-wheel upon the base, and which receives motion from an electric motor, 16, also mounted on the base, 10. Pivoted or hung upon said shaft, 12, is a light frame composed of a pair of similar parallel bars, 17, spaced apart to accommodate the worm-wheel and several cross-bolts, 18, which tie said bars 50 together, the bars being held apart by suit-

able spacing means. The frame, thus, provided at one end journals, by suitable bearings in the frame bars, a horizontal shaft, 19, which carries a series of radial fingers, 20, which constitute one set of stirrers, and parallel with said shaft and also supported by said frame is a similar shaft, 21, which also has radial fingers, 22, that form the other set of stirrers, the shaft, 21, being journaled and supported at one end by one bar of the 60 frame, and at the other end by a bracket arm, 23, bolted to said bar. Upon one end of said shaft, 19, is fixed a sprocket wheel, 24, and upon the other shaft is fixed a sprocket wheel, 25, in line with said sprocket wheel, 24, and a sprocket chain, 26, passes half way around the sprocket wheel, 24, and over the top of the other sprocket wheel, 25, to a sprocket wheel, 27, on the drive shaft, 12, the arrangement of chain and wheels being such 70 that one set of stirrers rotates in the opposite direction from the other and thereby all necessary agitation or stirring of the kettle contents can be secured without the potato chips or slices being thrown by centrifugal 75 force through motion of the liquid lard away from the stirrers or agitators. To support the stirrers or agitators in working position in the kettle or at a suitable height above the kettle when the kettle is to be emptied of 80 cooked potato chips or supplied with uncooked chips, a ratchet bar, 28, is pivoted at its lower end to the top of the base, 10, and extends upward therefrom, between the frame bars in position to have any one of 85 its series of ratchet teeth engaged with one of the cross or tie bolts, 18.

What I claim is:

A stirring mechanism having two sets of rotary stirring means situated side by side 90 and means for rotating the two sets in opposite directions simultaneously while in the material to be stirred, comprising sprocket wheels for the respective stirrers, a sprocket chain engaging both sprocket wheels, and a 95 driving sprocket wheel.

In testimony whereof I hereunto affix my signature.

ROLLER E. DUTT.
